UNITED STATES PATENT OFFICE.

JESSE STUBBS, OF MOUNT PLEASANT, ASSIGNOR OF TWO-THIRDS TO NELSON A. GRAY AND CARL L. MAHRENHOLZ, BOTH OF RED OAK, IOWA.

KILN FOR AND METHOD OF BURNING CLAY.

SPECIFICATION forming part of Letters Patent No. 338,206, dated March 16, 1886.

Application filed July 25, 1885. Serial No. 172,699. (No model.)

To all whom it may concern:

Be it known that I, JESSE STUBBS, a citizen of the United States, residing at Mount Pleasant, in the county of Henry and State of Iowa, 5 have invented a new and useful improvement in kilns for burning irregular conglomerate masses of clay into suitable material to be broken up for ballast, paving material, roadbeds, and such like purposes, of which the following is a specification.

My invention relates to a kiln built on the ground in open air, which may be constructed mostly or entirely of the clay required to be burned and the fuel used for burning it.

15 I am aware that clay has been burned for such uses in open air by first starting a coal fire on the ground and forming on it a heap of alternate layers of clay and coal while burning, which may be enlarged by raking out from 20 the burning mass an enlarged foundation, and in like manner building upon said extension, which subjects the workmen engaged to frequent contacts with the escaping smoke and gas therefrom, which is a source of great hindrance to their work and requires a great 25 sacrifice of their comfort. Said method also necessitates much stirring of the mass from the top while burning to give proper ventilation, which exposes the operators to dense 30 fumes of smoke and gas, greatly to the detriment of their health and comfort, and owing to the manner of thus burning by patches in detail, a less intensity of heat is produced in proportion to the amount of fuel 35 used than if simultaneous combustion of the whole mass were obtained, which also requires a greater length of time in burning and is liable to very imperfect action.

I am also aware that kilns for burning such 40 material have been constructed in open air by digging trenches or sub furnaces or flues in the ground at close intervals from each other, both lengthwise and transversely of said kilns, and that arches forming underlying furnaces 45 or flues above ground, similarly planned, have been made, all having their outer ends open, as a means of firing and ventilating the kiln while burning. The superstructure of said kilns consists of alternate layers of fuel and 50 lumps of dried clay, having the particles of fine or pulverized dirt excluded by sifting it

out, which is necessary to secure draft through the irregular openings formed between said chunks of dirt while burning, as no other provision is made to secure an upward draft or 55 intercommunication between the different layers or strata of fuel. Said preliminary preparation of the clay requires much labor and is liable to great loss by rains and other casualties while drying, causing it to crumble and 60 thereby become partially or entirely useless for the intended object. Great care is also required in handling said lumps of dried clay to prevent them from being pulverized in the construction of a kiln, which renders said kilns 65 and the process of their formation objectionable. They are further objectionable in having no means provided for manipulating or controlling the draft currents through the kiln while burning, which makes them liable 70 to very imperfect burning, and therefore great loss as a consequence. A still further objection to said kilns is that there is no provision for closing the mouth or outer ends of their flues or furnaces against heavy winds entering 75 them, which tends to drive the heat of the kiln to the leeward, and thereby also causes defective burning on the windward side.

The object of my invention is to provide a 80 means of burning clay in irregular conglomerate masses, without any preliminary preparation further than excavating and conveying it to the kiln, at one simultaneous heat throughout the kiln or heap, and of controlling the heat during the burning process after the construction of the same shall have been completed, requiring but little attention while 85 burning, and which will not expose the attendants to the fumes of smoke and escaping gas, thereby expediting the burning process 90 and utilizing the time of hands and labor to better advantage than by methods now known.

My invention consists in providing a kiln 95 constructed on the ground in open air convenient to the supply of material to be burned, having a series of horizontal heating-furnaces arranged at right angles with and crossing each other, and also intermediate ventilating-flues, all underlying the superstructure of the kiln, which consists of alternate layers of 100 fuel—such as coal-slack or like substances—and clay, and being provided also with ver-

tical draft-flues passing upward through said heap, which flues are constructed while building the kiln, and are made to connect at their lower ends with openings in the furnaces and 5 underlying ventilating-flues, and also caps or shutters for closing a requisite number of both the furnace mouths or openings below and the tops of chimneys or the vertical flues, for the purpose of controlling or shifting the draft to 10 such parts as may require greater heat while burning a kiln.

I will proceed to further describe my invention by referring to the accompanying drawings, which constitute part of this specification, of which— 15

Figure 1 is a perspective of part of a kiln formed for burning. It, however, is represented as having its farther end taken away and its near corner of superstructure removed, 20 for convenience in showing the arrangement of flues, furnaces, and the layers of coal and clay. Fig. 2 is a plan of a section embracing four consecutive intermediate squares or sections of furnaces and ventilating-flues as being detached. Fig. 3 is a plan of a transverse section of one of the vertical draft or smoke flues, and Fig. 4 is a perspective of one of the caps or shutters for closing the outer openings of furnaces and flues. 25

30 In the further description by illustration similar letters of reference will indicate like parts in the different figures, of which—

A are the main heating-furnaces, which may be constructed of kneaded clay, either molded 35 in regular form or may be rudely built without molding, and may, if desirable, have wood and kindling properly arranged within them for starting the fire, serving also as a means of support to the green arches before 40 drying. It will be observed that said furnaces are arranged in different series at right angles with and crossing each other, and at their respective crossings they interjoin. They are provided with openings e' over their cross- 45 ings, from which are built vertical draft or smoke flues e, which are for giving proper draft to the fire and for carrying off the smoke and steam from the drying clay. Said furnaces are also provided with smaller open- 50 ings S, which are arranged at close intervals, either in their sides or apex, as a means of communicating fire from within them to the bed of fuel outside of them, and underlying the general mass of clay, as well as also to 55 give passage for the smoke from said underlying bed of fuel.

a are ventilating-flues of much smaller dimensions than the furnaces above named, but may be constructed of same material and in 60 similar manner, and arranged at various angles, having branch connections with the furnaces A, as well as through the outer walls of the kiln. They also interjoin each other at their crossings, and at their general intersections are provided also with upward openings e' and vertical draft-flues e, for same purpose as above described. Said flues a are

also provided with intermediate or small openings, S, arranged along them at close intervals, for same purposes assigned for the 70 openings S in the furnaces A. Said furnaces A and ventilating-flues a may be left erected after first burning as a foundation for subsequent kilns, or taken for ballast, and new ones erected for subsequent use, as may be desired. 75

B is the lower and main layer of fuel, which may consist of coal-slack or other like cheap material, as may be most convenient or available, which may also be partially saturated with some highly-inflammable material—as 80 some of the inflammable oils—to hasten its ignition when fired.

b are intermediate and final layers of like fuel placed between the different layers of clay and on top of the upper one. 85

C are said layers of clay, which are shoveled or may be wheeled or carted in without any particular preparation. The layers B and b of fuel and C of clay, respectively, extend over the whole area of the kiln (outer walls excepted.) They will, however, be diminished in size as their height increases, as a means of forming batter-walls of the sides, which walls consist of a thin layer of kneaded clay. 90

c are chunks of kneaded clay, which may 95 be molded or otherwise suitably shaped, which are laid, as shown at Fig. 3, in successive layers one upon another as the height of material increases in the construction of the kiln, thereby forming vertical draft and smoke flues 100 around the temporary wooden box-flues e, which serve in their stead after the wooden flues shall have burned out; or with proper care in construction the wooden flues e may be dispensed with, as they are intended only 105 to serve as guides against which to lay the clay chunks c in building said flues.

It will be observed that the clay chunks c are laid so that an open space is left between them at their inner corners, which openings 110 serve as passages for the entrance of smoke and steam into said flues throughout their entire length. Said chunks are held in place by means of the fuel being placed in the angles formed by them, and by the layers of clay 115 resting on and otherwise binding them, which is sufficient for the purpose after the fuel around them shall have burned away. Said flues, as before stated, are erected over and are connected with the openings e' in the furnaces A and at the general intersections of the flues a, and extend through the top of the kiln. 120

Metallic flue caps or shutters, Fig. 4, are provided for closing the mouths or outer open 125 ends of the furnaces and flues, either at the base or on top of kiln, when necessary, as a means of regulating the draft by checking it at one or more places as a means of diverting its channel to other points requiring greater 130 heat, which manipulation is effected by thus closing and opening the proper furnaces and flues, respectively, so as to throw a stronger current or draft through channels requiring

increased heat. They are also used on the windward sides of a kiln to prevent too strong currents blowing through the furnaces.

Having thus fully shown the construction 5 of my improved kiln, so as to enable others to understand the same, it is operated by filling the underlying furnaces and flues with light inflammable fuel suitable for kindling, (if the same shall not have been done at a previous time,) and as nearly simultaneous as practical to fire or ignite all of said furnaces, which will cause a quick and produce an intensely-hot fire, sufficient for speedily burning the clay in the kiln to a very hard substance 10 suitable for the purposes above named by breaking it into suitable pieces. If, however, it should from any event become necessary to continue the burning longer after the supply of fuel originally arranged shall have been exhausted, fresh supplies of suitable fuel may be 15 put into the furnaces sufficient to prolong the burning any required length of time; and after the burning process shall have been completed the kiln may be quickly cooled for 20 handling the burned material by opening all 25

of the furnaces and flues, so as to allow a free circulation of air through them.

What I claim as new, and desire to secure by Letters Patent, is—

1. In combination with the underlying furnaces and ventilating - flues having upward openings e' of a clay-burning kiln having its superstructure composed of successive alternate layers of fuel and clay, the vertical flues or chimneys e , connecting by means of the 30 openings e' with said horizontal underlying furnaces and flues, and also by lateral openings with the different layers of fuel, substantially as shown, for the purposes specified.

2. In combination with the underlying furnaces and flues of a clay-burning kiln and vertical ventilating and smoke-discharging flues, 35 all having outward openings, the shutters or flue-caps, Fig. 4, substantially as shown, for the purposes specified.

JESSE STUBBS.
